UNITED STATES PATENT OFFICE.

JOSEPH THEODORE HOMAN, OF CINCINNATI, OHIO.

DESIGN FOR A METAL BORDER FOR PLATE.

No. 38,862.

Specification for Design.

Patented Oct. 22, 1907.

Application filed July 29, 1907. Serial No. 386,173. Term of patent 7 years.

To all whom it may concern:

Be it known that I, JOSEPH THEODORE HOMAN, a citizen of the United States, residing at Cincinnati, in the county of Hamilton and State of Ohio, have invented a new, original, and ornamental Design for Metal Border for Plate, of which the following is a specification, reference being had to the accompanying drawings, forming a part thereof.

The figure is a plan view of a metal border for plate, showing my new design.

I claim:

The ornamental design for metal border for plate as shown.

JOSEPH THEODORE HOMAN.
